W. T. GARDNER.
VERTICAL RETORT FOR CARBONIZING COAL.
APPLICATION FILED DEC. 24, 1920.

1,407,996.

Patented Feb. 28, 1922.

Attorney

UNITED STATES PATENT OFFICE.

WILLIAM TEMPLE GARDNER, OF BRUERN, ENGLAND, ASSIGNOR TO ISBELL-PORTER COMPANY, OF NEWARK, NEW JERSEY, A CORPORATION OF NEW YORK.

VERTICAL RETORT FOR CARBONIZING COAL.

1,407,996.

Specification of Letters Patent. Patented Feb. 28, 1922.

Application filed December 24, 1920. Serial No. 433,028.

To all whom it may concern:

Be it known that I, WILLIAM TEMPLE GARDNER, a subject of Great Britain, residing at Bruern, Surrey, England, have invented certain new and useful Improvements in Vertical Retorts for Carbonizing Coal, of which the following is a specification.

My invention relates to retorts and more especially to that type used for carbonizing coal and has for its primary object to allow for the escape of the products of distillation from over the whole surface of the top of the retort thereby insuring a more efficient and uniform withdrawal of said products of distillation than heretofore accomplished in this class of retorts.

Further objects and advantages of the invention will appear from the detailed construction and arrangement of said parts comprising the invention and in the manner of assembling and using the same.

The cross section in plan of a vertical retort is generally oblong and the off-take of volatile products from the mouth-piece of the retort is usually at one end of this oblong. When the major axis of the retort is increased in order to obtain a larger unit the volatile products given off on the side of the retort away from the outlet have to pass across the retort before they reach the outlet.

A more uniform withdrawal of products is secured by this invention, consisting in a construction which allows of escape from over the whole surface of the top of the retort.

Heretofore the mouth-piece has been practically a continuation of the charging hopper and has become filled with coal so that there has been no passage for gas except at that end of the mouth-piece at which the off-take is situated.

By this invention the chamber within the mouth-piece is subdivided by partitions which confine the coal as it leaves the hopper and until it has descended through the mouth-piece, so that there is a free space at each end of the mouth-piece; each partition has an opening at its upper part permitting passage of gas across the coal in the mouth-piece.

The invention consists of structural characteristics and relative arrangements of elements which will be hereinafter more fully described and particularly pointed out in the appended claims.

Similar reference characters indicate the same parts in the several figures of the drawings in which:

Fig. 1 is a longitudinal vertical section and 60

Fig. 2 is a cross section through a mouth-piece constructed according to this invention.

In the drawings *a*, is the casting constituting the top of the retort and *b* is the casting constituting the mouth-piece. The latter has transverse partitions *c* and these are extended by like partitions *d* in the casting *a*.

Each partition *c* has an opening *e* the 70 shape of which is determined by the angle of repose of the coal on the inclined bottom of the hopper *f*, the object being to permit the maximum opening while preventing flow of coal through the opening. Thus the coal 75 does not spread laterally into the retort until it has arrived at the lower edge of the partitions *d* and the products can travel up over the whole top surface of the retort. The arrows in Fig. 1 indicate the flow of 80 products.

What I claim is:—

1. A feeding device for a vertical retort comprising a top section for the retort, a hopper, a mouth-piece having an inclined 85 side and an outlet and interposed between and communicating with said top section and hopper, separated partitions within said mouth-piece and forming a passageway through the mouth-piece from the hopper into the top section, each of said partitions having an opening adjacent to the side of the mouth-piece opposite to its inclined side.

2. A feeding device for a vertical retort 95 comprising a top section for the retort, a hopper having an inclined bottom, a mouth-piece having an outlet and an inclined side forming a continuation of the inclined bottom of said hopper and interposed between and 100 communicating with said top section and hopper, separated partitions within said mouth-piece and extending into the top section of the retort and forming a passageway through the mouthpiece from the hopper 105 into the top section, each of said partitions having an opening adjacent to the side of the mouth-piece opposite to its inclined side.

In testimony whereof I affix my signature.

WILLIAM TEMPLE GARDNER.
